CLAIM

The ornamental design for a shroud cover component for a temperature control system, as shown and described.

DESCRIPTION

FIG. 1 is a top perspective view of a shroud cover component according to the present invention;

FIG. 2 is a bottom perspective view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front elevation view thereof; and,

FIG. 8 is a rear elevation view thereof.

The features shown in broken lines depict environmental subject matter only and form no part of the claimed design.
